PLATFORM COVER ROUGHENING AND
GRADING MACHINE

Leo F. Exley, Johnson City, N. Y., assignor to
Endicott Johnson Corporation, Endicott, N. Y.,
a corporation of New York

Application June 23, 1947, Serial No. 756,571

20 Claims. (Cl. 69—1)

1

This invention is a novel machine for roughening and grading strip material, particularly the portions thereof, and the principal object of the invention is to provide a machine for roughening and grading the side portions of strip stock, such as the skin side of leather, or similar material, used as side covers for platform soles.

Roughening the surface of such material has heretofore been the accepted standard practice, the margins of said platform covers being prepared by using grinding wheels, sand paper covered or glued set-up wheels or wire brushes, or by sanding by hand, using suitable abrasive papers or cloths, or by scraping or buffing, using a knife or buffer, it being necessary to roughen the surface to receive cement or similar adhesive agent so that the adhesive will adhere firmly thereto and to the parts of the shoe sole to which it is attached. It is important that the treated area must be definitely limited to straight lines so that no part of the roughened skin surface will be seen after the shoe is assembled. It is obvious that hand work has no place in quantity production, and, even with the use of power-driven agents, the work must be presented by hand, and it is difficult, if not impossible, to obtain and maintain uniform margins consistently. Attempts have been made to alter existing (skiving) machines to adopt them to the operation required. Such attempts have not been successful and at the present time all manufacturers of cemented shoes are performing the operation under discussion in some of the ways above enumerated.

My novel machine consists essentially of a suitable guide or entrance into which the operator inserts one end of the strip to be treated, whereupon feeding mechanism carries the strip over a particularly designed fixed surface cooperating with treating wheels which engage the strip and function while the strip is moving over the surface, and feeding mechanism carrying the finished work away from the treating wheels and discharging same.

One object of my invention is to provide a machine which will quickly, effectively, and economically clean and properly prepare the surface of any material or part to which cement is to be applied with the object of subsequently attaching such part to some other part which has been similarly treated and prepared.

Another and important object of my invention is to provide a device which may be quickly and easily adjusted and set so that a predetermined and limited area only of the strip may be treated, and the line of demarcation between the original

2

and treated surface will be well defined, uniform and specifically, in this case, straight.

A further object of my invention is to provide a device having adjustments so that the treating wheels may be positioned and set in such a way that any amount of material may be removed from the strip being treated. In my machine, as constructed, this particular adjustment permits a range of treatment from the minimum required to effect a satisfactory surface, to a maximum amount wherein the edges are thinned down to a condition comparable to work performed by the various skiving machines which are commonly used in the shoe manufacturing industry.

Skiving the edges of parts as practiced in the shoe industry consists in cutting or shaving the marginal portion of a part at an angle so that the margin tapers from full thickness at the beginning of the cut to a much thinner outer edge. The purpose of skiving edges is to facilitate such operations as folding the edge of the part on itself or the lapping and attaching to another part. Such tapering and thinning of the edges of platform covers is desirable and sometimes necessary in order that the lapped-over portion will better and more easily conform to the in-and-out curves which constitute the irregular outline of the platform, and in order that the lapped-over portion of the cover will lay flat and adhere closely to the platform without wrinkling or buckling. To insure intimate contact and a secure fastening and to provide good appearance in the finished shoe, both sides of the platform with its cover must be reasonably smooth, and such conditions cannot be obtained unless the edges of the cover strip are thinned to a known and uniform thickness.

For economy in manufacturing, covers are usually cut from waste or scrap stock and so are bound to be of varying grades and thickness. However, regardless of such variations, my machine not only produces an ideal surface to receive cement, but also simultaneously and automatically thins the edges to a predetermined degree and so facilitates manipulation in applying the cover, and insure smooth surfaces of the finished platform.

I will explain the invention with reference to the accompanying drawings, which illustrate one practical embodiment thereof, to enable others familiar with the art to adopt and use the same; and will summarize in the claims, the novel features of construction, and novel combinations of parts, for which protection is desired.

In said drawings:

Figure 1 is a top plan view of my novel roughening machine.

Fig. 2 is an enlarged front view, partly in section, of the right hand side of the machine.

Fig. 3 is an enlarged section on the line 3—3, Fig. 1.

Fig. 4 is an enlarged plan view showing a portion of the treated leather strip.

Fig. 5 is a transverse section on the line 5—5, Fig. 4.

Fig. 6 is an enlarged top plan view of the strip receiving slot and underlying parts.

Fig. 7 is an enlarged section through the strip feeding block in way of the brushes.

Fig. 8 is an enlarged front view, partly in section, showing the strip feeding block and its adjustments.

Fig. 9 is an enlarged elevation showing the brush shaft adjusting means.

The drawing shows two complete units which are substantially identical, driven by one motor through an interposed speed reducer; the arrangement being for economy in construction and operation, and to permit treating by the operator of two different widths of stock ordinarily used to cover a platform sole; one width being that used around the heel portion of the platform which is much thicker than the forepart of the platform and hence requires the use of a wider strip.

I will now describe the function and action of the various parts of my machine and for purposes of description I will consider only one unit in that both are alike, and hence I will use the same reference numerals to designate like parts on all views of both units.

The machine preferably comprises a bed plate 1 of any desired shape, same being preferably substantially rectangular. On or adjacent the center-line thereof, towards the rear end 1a (Fig. 1) is a prime mover, preferably an electric motor 2 having foot brackets 2a (Fig. 2) secured to base 1 by bolts 3 (Fig. 2), motor 2 having a shaft 2b carrying belt pulleys 4 and 5 (Fig. 1) at its rear end and carrying a coupling member 6 at its front end engaging a complementary coupling member 7 on the shaft 8a of a speed-reducing mechanism 8 having opposed driven shafts 8b and 8c extending at right angles to the shaft 8a (Fig. 1), said shafts carrying on their outer ends sprockets 8d. The couplings 7 and 8 may be of standard type; and the speed of motor 2 is materially lowered by speed-reducer 8 to transmit a comparatively slow speed of rotation to sprockets 8d.

Parallel with the shafts 8b—8c of speed reducer 8 are aligned shafts 9 at both sides of speed reducer 8, each shaft carrying a sprocket 9a on its inner end opposite its related sprocket 8d of speed reducer 8, a chain 10 running around the pairs of sprockets 8d—9a. Preferably sprockets 9a are larger than sprockets 8d for the purpose of further reducing the speed of the shafts 9 with respect to the motor 2. Each shaft 9 is journaled in brackets 11 mounted upon the base 1, said brackets 11 also carrying journals for shafts 12 which are spaced from but parallel with the shafts 9, as shown in Fig. 1. On the outer ends of each pair of shafts 9—12 are sprockets 9c and 12c respectively, around which run chains 13 whereby the shafts 9 and 12 are rotated in the same direction and at the same speed by the speed reducer shafts 8b and 8c respectively.

On each pair of shafts 9 and 12 adjacent the centers thereof are aligned feed wheels 14 and

15 respectively (Fig. 3) having their peripheries slightly spaced apart, said feed wheels being of same size as shown, and being obviously rotated in the same direction, i. e., in the direction of the arrows 14a and 15a (Fig. 3) for the purpose hereinafter set forth.

Associated with each pair of feed wheels 14—15 is a guide 16 consisting of a base block 16a of length sufficient to embrace the wheels 14—15 and to extend to the point adjacent the front end 1b of base plate 1, said block 16a being held in position by means of screws or bolts 17, as shown. Block 16a is of height substantially equal to the distance of the axes of shafts 9 above base 1 (Fig. 3) and each block 16a has a rectangular axial slot 16b (Fig. 2) in its upper face extending to points adjacent the sides thereof.

Upon each block 16a is a head block 16c (Fig. 2) having a tongue 16d at its lower end of less width than the slot 16b of base block 16a, the sides of the tongue 16d being engaged by screws 18 tapped through bores in the sides of the base block 16a opposite the slot 16d whereby adjustment of the screws 18 will permit the head block 16c to be shifted laterally of the base block 16a within the limits of the slot 16d. Head block 16c is of somewhat less height than the upper peripheries of the feed wheels 14—15, and one side of the upper portion of head block 16c is cut away as at 16e for the reception of an adjusting block 16f (Fig. 1) having its upper face terminating in the plane of the upper face of head block 16c; and a thumb screw 19 extends through the adjusting block 16f and into the upper portion of head block 16c so that the adjusting block 16f may be shifted laterally on the head block 16c by adjustment of screw 19.

Seating upon the upper faces of the adjusting block 16f and head block 16c is a plate 16g having a thickened edge portion 16h seating upon the top of the head block 16c and secured thereto by means of screws 20 (Fig. 1). The opposite edge of the cover plate 16g seats upon a raised outer edge portion 16k of the adjusting block 16f and is secured thereto by screws 21 passing through slots in the plate 16g and into the edge portion 16k.

By the above construction a strip-receiving slot 16x is provided between the tops of the head block 16c and adjusting block 16f and the under side of the cover plate 16g, as shown in Fig. 2, said slot being disposed slightly below the upper peripheries of the feed wheels 14—15. Blocks 16a and 16c and plate 16g are cut away as at 16m (Fig. 3) in way of the wheels 14—15, leaving openings at the top of the guide 16 through which the wheels 14—15 slightly project so as to engage the strip S (Figs. 2, 4, 5) which is fed thereover through the slot 16x in the guide 16. As shown, the plate 16g is provided with a centrally-disposed slot 16n at its front end to facilitate entry of the strip S into the slot 16x.

By the above construction the position of the slot 16x laterally with respect to the feed wheels 14—15 may be varied by manipulating the screws 18. Also, the width of the slot 16x may be varied by manipulating the screws 19.

Cooperating with the front feed wheel 14 is a pressure wheel 22 mounted on a shaft 23 disposed directly above the shaft 9, said shaft 23 being mounted in the same brackets 11 in which shaft 9 is journaled, the bearings for shaft 23 being carried in blocks 24 (Fig. 3) vertically adjustably mounted in the brackets 11, the vertical position of the blocks 24 being regulated by screws 25

passing through heads 26 at the upper ends of the brackets 11 (Fig. 3) so that the pressure on the strip S when passing between the wheels 9 and 22 may be nicely regulated.

Aligned with the feed wheels 14—15 adjacent the rear end 1a of the base 1 at opposite sides of the motor 2 are brackets 27 (Fig. 3) secured by bolts 28 to the base 1a, each bracket carrying spaced journals 27a for substantially parallel shafts 29 disposed at opposite sides of the feed wheels 14—15, said shafts 29 carrying intermeshing gears 30—31 on their inner ends, the inner shafts 29 also carrying belt pulleys 32 opposite the pulleys 4 and 5 respectively on the shaft of motor 2; and belts 33 run around the respective pairs of pulleys 32—4 and 5—32.

Bearings 27 are of a self-aligning type so as to permit the angularity of shafts 29 to vary slightly from their truly parallel relation without disengaging the intermeshing gears 30—31. The forward ends of shafts 29 are mounted in bearings 34 respectively, which are adjustable vertically and laterally of the feed wheels 14—15, the bearings 34 for the shafts 29 being also of the self-aligning type so as to prevent binding of the shafts 29 in their bearings 34 and 27a when the angularity of the shafts 29 of the pairs become shifted from a truly parallel relation. As shown in Fig. 3, the shafts 29 slope downwardly and forwardly in their bearings 27a and 34 respectively and carry on their front ends circular wire brushes 35 (Figs. 2 and 3).

The bearings 34 are carried by arms 34a, more particularly shown in Figs. 1 and 2, which arms slope upwardly and outwardly adjacent the brackets 11 and overlie substantially correspondingly inclined portions 11x of the brackets 11, the upper ends of the inclined portions 11x of the brackets 11 having upwardly flanged ends 11y, as shown more particularly in Fig. 2.

Between the under sides of the arms 34a and the upper faces of the inclined portions 11x of brackets 11 are wedge-shaped members 36 (Fig. 2) which may be shifted axially of the surfaces 11x by adjusting screws 37 anchored in the upper ends of the wedges 36 and threaded into bores in the flanged ends 11y of the brackets, said screws being provided with lock nuts 38 (Fig. 2). Thus, when the lock nuts 38 are loosened, the wedges 36 may be shifted axially of surfaces 11x by manipulation of the screw 37 to raise or lower the bearings 34 with respect to the base 1.

The arms 34a are provided with axial slots 34b (Fig. 2) through which extend centering bolts 39 (Fig. 2) which are anchored in the inclined surfaces 11x to maintain the arms 34a aligned on the surfaces 11x in all positions of adjustment of the arms 34a thereon. The upper ends of arms 34a are flanged upwardly as at 34c (Fig. 2) parallel with the flanges 11y, and adjusting screws 40 are anchored in the flanges 34c and pass through tapped bores in the flanges 11y, and are provided with lock nuts 41, whereby when the lock nuts 41 are loosened, and the screws 40 rotated, the arms 34a will be shifted axially of the surfaces 11x.

By the above construction, the wire brushes 35, which are disposed adjacent both sides of the guide 16, may be raised or lowered with respect to the base or shifted inwardly or outwardly with respect to the axes of the guide, for the purpose hereinafter explained, by merely adjusting the thumb screws 37—40, and such adjustments, by reason of the self-aligning bearings 27a and 34,

will not cause binding of the shafts 29 in their bearings.

As shown in Fig. 2, both sides of the guide 16 at its end in way of the brushes 35 are formed 5 as arcs 16y of circles whose centers are substantially the axes of rotation of the circular brushes 35, and as shown in Fig. 2, when the strip S is inserted in the slot 16x, the sides of the strip S will be deflected downwardly by the brushes 35 10 so as to lie upon the arcuate surface 16y so that their marginal portions will be roughened by the wire brushes 35, the roughened portions at the sides of the strip S being denoted in Fig. 4 by the reference character S' while the central portion S2 remains unroughened. The extent of the 15 roughening of the sides of the strip S depends upon the adjustment of the adjusting block 16f on the head block 16c through manipulation of the thumb screws 19.

In order to assist proper feeding of the strip, 20 a pressure roller 42 (Fig. 3) is arranged over the rear feed wheel 15, said roller 42 being journaled in pivoted arms 43 connected to a bracket 44 attached to the bearing bracket 27 between the journals 27a; and a flat spring 45 is secured to the bracket 44 and normally urges the arms 43 downwardly into yieldable contact with feed roller 15 so that the pressure roller 42 will assist 25 in passing the roughened strip S out of the machine. The wheels 22 and 42 may if desired be power driven, but as shown are mere idlers.

The wire brush wheels 35 are of standard type, 30 and the respective shafts 29 of each set, by reason of the intermeshing gears 30—31, rotate in opposite directions, i. e. in the direction of the arrows 35a (Fig. 2) so as to force the edges of 35 the strip S in the guide 16 down upon the arcuate surfaces 16y thereof.

The bearings 27a and 34 are of a standard self-aligning type so as to function properly even 40 though the shafts are not in alignment, i. e. at right angles to the outer faces of the bearings. The self-aligning feature of the bearings allows 45 for the required shifting of shafts 29 into various positions in adjusting the brushes for various conditions of treatment of the edges of the strip S.

It is obvious that the maximum movement of 50 the brushes 35 required for adjusting would be less than the thickness of the strip S being processed, in fact the range of movement is so little that the bearings 27a and 34, the gears 30—31, the pulleys 32 and the driving belts 33 all function properly and there is no need of special 55 equipment such as joints, couplings, pivots, etc., to compensate for the fact that the shafts 29 will under some circumstances diverge from exact parallel relationship.

The guides 16 provide slots 1x or passage from 60 the front 16 of the base (nearest the operator) to a point immediately in front of the feed wheels 14 and 15. By means of adjusting screws 19 the width of the slot 1x may be altered and varied 65 so as to accommodate and accurately guide and direct to the feed rolls 14—15 any width of strip S. Ordinarily the guide slot 1x is located centrally in relation to the feed wheels 14—15 and the strip stock S treated has an equal area or margin of roughening S' along each edge. There 70 are however conditions which require a strip S having a wider margin of treatment on one edge S' than on the opposite edge, and for this purpose I have also provided means, i. e., screws 18 for moving the guide slot 1x to either the right 75 or the left of the center line of the feed wheels

14—15, fixing the guide slot 16x in position to produce a strip S having any degree of variation or margin required.

The arcuate portions 16y of the guide 16 are of a radius greater than the radius of the wire brush wheels 35 by approximately the average thickness of the stock S used for the platform covers. This relation of the radius of the brush wheels and the arcuate portions 16y of the guide is important, in that it permits the proper roughening of the surface of thin stock without removing any substance.

In operation, the operator inserts the strip S in the slot 16x in the guide 16 and pushes it forward (away from him) until it enters between the feed wheels 14 and 22. At this point the strip S, brought in contact with the brush wheels 35 which drag the unsupported edges downward against the arcuate sides 16y of the guide, scratch and roughen the surface of the strip S progressively as at S' as it is pulled along by the feed wheels 14 and 15. As the strip S progresses along the guide 16 it is engaged by the feed wheels 15 and 42 which pull the strip S at the same rate, and so when a strip is entered for treatment it progresses through the machine at a constant steady rate without interruption or need of attention until, when completed, it is discharged at the back of the machine.

My machine does not require any skill or particular dexterity on the part of the operator. The operator has only to feed the strips S through the strip receiving slot 16x and to pick up and stack the completed work, discharged at the back. Adjustments are simple and easy to operate and obvious in nature, and once set require no further attention. The work produced is uniform, and loss is substantially eliminated.

Each guide 16 is obviously interchangeable with other sizes or widths of guides as required. The adjustment and positioning of the wire brush wheels 35 is accomplished by the manipulation of the adjusting screws 37 and 40. The screws 40 move the wheels 35 inwardly and outwardly in relation to the arcuate surfaces 16y of the guide 16, and the screws 37 operate the wedges 36 which raise and lower the wheels 35.

This combination of in-and-out, and up-and-down movement of the wheels 35 enables the operator to adjust and position the wheels independently, and thus meet any and every possible requirement.

I do not limit my invention to the exact form shown in the drawings, for obviously changes may be made therein within the scope of the claims.

I claim:

1. A machine for roughening the side portions of strip material comprising a base; a prime mover mounted thereon; parallel shafts journaled on the base and driven by the prime mover in the same direction; aligned feed wheels on the parallel shafts rotating at the same peripheral speed; pressure means on the base above and cooperating with the respective feed wheels; a guide aligned with the feed wheels for directing the strip material between the feed and pressure means, said guide having arcuate portions extending downwardly and outwardly from its opposite upper side edges; rotary brushes at opposite sides of the guide and having their axes disposed substantially coaxially of the arcuate portions and their peripheries lying closely adjacent the respective arcuate portions; means for rotating the brushes in directions to flex the side edge

portions of the strip material in the guide downwardly upon the arcuate side portions of the guide; means for raising and lowering the brushes with respect to the arcuate portions of the guide; and means for shifting the brushes towards or from the said arcuate portions.

2. In a machine as set forth in claim 1, a pair of brush shafts at opposite sides of the guide carrying at one end said rotary brushes respectively, a bracket mounted on the base carrying self-aligning bearings for the opposite ends of the brush shafts; means for rotating the brush shafts by the prime mover; other brackets at opposite sides of the guide mounted on the base adjacent the brush ends of the brush shafts having surfaces sloping downwardly towards the guide; and plates on said surfaces carrying self-aligning bearings for the brush ends of the brush shafts.

20 3. In a machine as set forth in claim 2, said means for rotating the brush shafts comprising intermeshing gears on said opposite ends of the brush shafts; a pulley on one shaft disposed opposite a second pulley on the prime mover shaft; 25 and a belt running around said first and second pulleys respectively.

4. In a machine as set forth in claim 2, said means for raising and lowering the brushes comprising wedge-shaped blocks interposed between the plates and inclined bracket surfaces; and screws anchored in the wedges and passing through threaded bores in the brackets for shifting the wedges toward and from the guide.

35 5. In a machine as set forth in claim 2, said means for shifting the rotary brushes towards or from the arcuate portions of the guides comprising screws anchored in the plates and passing through tapped bores in the brackets, for shifting the related bearings of the brush shafts towards or from the guide.

40 6. A machine for roughening the side portions of strip material, comprising a base; a prime mover mounted thereon; parallel shafts journaled on the base and driven by the prime mover in the same direction; aligned feed wheels on the parallel shafts rotating at the same peripheral speed; pressure wheels journaled on the base above and cooperating with the respective feed wheels; a guide aligned with the feed wheels having a strip receiving slot for directing the strip material between the feed and pressure wheels, said guide having arcuate portions extending downwardly and outwardly from its opposite upper side edges; means for shifting the guide laterally of the aligned feed wheels; means for adjusting the width of the guide slot; rotary brushes at opposite sides of the guide having their axes disposed substantially coaxially of the arcuate portions and their peripheries lying closely adjacent the respective arcuate portions of the guides; means for rotating the brushes in directions to flex the side edge portions of the strip material in the guide downwardly upon the arcuate side portions of the guide; means for raising and lowering the brushes with respect to the arcuate portions of the guide; and means for shifting the brushes towards or from the said arcuate portions of the guide.

7. In a machine as set forth in claim 6, a pair of brackets having journals for the parallel shafts, and carrying vertically movable journal blocks for the leading pressure wheel disposed above the front feed wheel; means for adjusting the position of said blocks; and a spring pressed frame

carrying the trailing pressure wheel disposed above the rear feed wheel.

8. In a machine as set forth in claim 6, said guide comprising a base block mounted on the base and having a slot in its upper face; a head block upon said base block having a tongue entering the slot of less width than the slot; said head block having a recess in one upper corner; an adjusting block in said recess of less width than the recess and having its upper face disposed in the plane of the upper face of the head block; means for securing said blocks together; and a cover plate mounted on the head block and adjusting block and having a central portion spaced from the upper faces of the head block and adjusting block and defining the strip receiving slot.

9. In a machine as set forth in claim 8, said means for shifting the guide laterally comprising opposed screws passing through threaded bores in the sides of the base block entering the slot and engaging the sides of the tongue of the head block; and said means for adjusting the width of the guide slot comprising screws passing through threaded bores in the sides of the adjusting block and having their inner ends anchored in the head block in way of the recess; said adjusting block having a raised outer edge portion slidably engaging the under side of the cover plate, said raised edge portion forming one side wall of the guide slot.

10. In a machine as set forth in claim 6, said guide comprising a base block mounted on the base and having a slot in its upper face; a head block provided with said strip receiving guide slot and mounted upon said base block and having a tongue entering the slot of less width than the slot; and said means for shifting the guide laterally comprising opposed screws passing through threaded bores in the sides of the base block entering the slot and engaging the sides of the tongue of the head block.

11. In a machine as set forth in claim 6, said guide comprising a block mounted on the base and having a recess in one upper corner; an adjusting block in said recess of less width than the recess and having its upper face disposed in the plane of the upper face of the first block; a cover plate mounted on the first block and adjusting block and having its central portion spaced from the upper faces of the first block and adjusting block and defining the strip receiving guide slot, and said means for adjusting the width of the guide slot comprising screws passing through threaded bores in the sides of the adjusting block and having their inner ends anchored in the first block in way of the recess; and said adjusting block having a raised outer edge portion slidably engaging the under side of the cover plate, said raised edge portion forming one side wall of the guide slot.

12. A machine for roughening the side portions of strip leather side covers for platform soles, comprising a base; a prime mover mounted on the base; a speed reducing mechanism operated by the prime mover and having opposed driven shafts; pairs of parallel shafts journaled on the base at opposite sides of the speed reducing mechanism respectively and driven by the respective opposed driven shafts in the same direction; aligned leading and following feed wheels on the respective pairs of shafts rotating at the same peripheral speed; aligned leading and following pressure wheels journaled on the base above and cooperating with the feed wheels respectively; guides aligned with the aligned feed wheels re-

spectively having strip receiving slots for directing the strips between the feed wheels and pressure wheels, said guides having opposed arcuate portions extending downwardly and outwardly from their upper side edges; means for shifting the guides laterally of the aligned feed wheels; means for adjusting the width of the guide slots; rotary brushes at opposite sides of the guides having their axes disposed substantially coaxially of the arcuate portions of the guides, the peripheries of the brushes lying closely adjacent the arcuate portions of the guides; means for rotating the brushes in directions to flex the side edges of the strip material in the guides downwardly upon the arcuate side portions of the guides; means for raising and lowering the brushes with respect to the arcuate portions of the guides; and means for shifting the brushes towards or from the said arcuate portions of the guides.

13. In a machine as set forth in claim 12, pairs of brackets having journals for the related pairs of shafts and carrying vertically movable journal blocks for the leading pressure wheels disposed above the leading feed wheels; means for adjusting the position of said blocks; and spring pressed frames carrying the trailing pressure wheels disposed above the following feed wheels.

14. In a machine as set forth in claim 12, each guide comprising a base block mounted on the base; and having a slot in its upper face; a head block upon said base block having a tongue entering the slot and of less width than the slot; said head block having a recess in one upper corner; an adjusting block in said recess of less width than the recess and having its upper face disposed in the plane of the upper face of the head block; means for securing said blocks together; and a cover plate mounted on the head block and adjusting block and having its central portion spaced from the upper faces of the head block and adjusting block and defining the strip receiving slot.

15. In a machine as set forth in claim 14, and said means for shifting each guide laterally comprising opposed screws passing through threaded bores in the sides of the base block entering the slot and engaging the sides of the tongue of the head block.

16. In a machine as set forth in claim 14, and said means for adjusting the width of the guide slot comprising screws passing through threaded bores in the sides of the adjusting block and having their inner ends anchored in the head block in way of the recess; said adjusting block having a raised outer edge portion slidably engaging the under side of the cover plate, said raised edge portion forming one side wall of the guide slot.

17. A machine for roughening the side portions of strip leather side covers for platform soles, comprising a base; a prime mover mounted on the base; a speed reducing mechanism operated by the prime mover and having opposed driven shafts; pairs of parallel shafts journaled on the base at opposite sides of the speed reducing mechanism respectively and driven by the respective opposed driven shafts in the same direction; aligned leading and following feed wheels on the respective pairs of shafts rotating at the same peripheral speed; aligned leading and following pressure wheels journaled on the base above and cooperating with the feed wheels respectively; guides aligned with the aligned feed wheels respectively having strip receiving slots for direct-

11

ing the strips between the feed wheels and pressure wheels, said guides having opposed arcuate portions extending downwardly and outwardly from their upper side edges; means for shifting the guides laterally of the aligned feed wheels; means for adjusting the width of the guide slots; rotary brushes at opposite sides of the guides having their axes disposed substantially coaxially of the arcuate portions of the guides, the peripheries of the brushes lying closely adjacent the arcuate portions of the guides; means for rotating the brushes in directions to flax the side edges of the strip material in the guides downwardly upon the arcuate side portions of the guides; means for raising and lowering the brushes with respect to the arcuate portions of the guides; means for shifting the brushes towards or from the said arcuate portions of the guides, pairs of downwardly and inwardly inclined shafts at opposite sides of the guides carrying at their lower ends the pairs of rotary brushes respectively; brackets mounted on the base carrying pairs of self-aligning bearings for the upper ends of the pairs of inclined shafts; means for rotating the pairs of shafts in opposite directions by the prime mover; other brackets at opposite sides of the guides mounted on the base adjacent the lower ends of the inclined shafts having surfaces sloping down-

12

wardly towards the guides; and plates on said surfaces carrying self-aligning bearings for the lower ends of the inclined shafts.

18. In a machine as set forth in claim 17, and said means for rotating the pairs of inclined shafts comprising intermeshing gears on the upper ends of the pairs of inclined shafts; a pulley on one shaft of each pair disposed opposite a second pulley on the prime mover shaft; and belts running around said first and second pairs of pulleys respectively.

19. In a machine as set forth in claim 17, and said means for raising and lowering the brushes comprising wedge-shaped blocks interposed between the plates and sloping bracket surfaces; and screws anchored in the wedges and passing through bores in the brackets for shifting the wedges toward and from the guides.

20. In a machine as set forth in claim 17, and said means for shifting the brushes towards or from the arcuate portions of the guides comprising screws anchored in the plates and passing through tapped bores on the brackets for shifting the lower bearings of the inclined shafts towards or from the guides.
